(57) **CLAIM**

The ornamental design for a display screen with keyboard graphical user interface, as shown and described.

DESCRIPTION

FIG. 1 is a front view of a display screen with keyboard graphical user interface showing the new design; and, FIG. 2 is a front view of a display screen showing an alternate embodiment thereof.

The broken line showings of the display screen in FIGS. 1 and 2, and of the circular symbols in FIG. 2, are for environmental purposes only and form no part of the claimed design.

1 Claim, 2 Drawing Sheets
